WASHING, CLEANING, EMULSIFYING AND
WETTING-OUT AGENT

Walther Schrauth, Berlin-Dahlem, Germany, assignor, by mesme assignments, to Unichem Chemikalien Handels A.-G., Zurich, Switzerland, a corporation of Switzerland

No Drawing. Application April 30, 1930, Serial No. 443,808. In Germany April 30, 1929

9 Claims. (Cl. 252—1)

It has already been proposed to use pyridine and other nitrogen-containing organic bases having a structure similar to benzene as wetting-out and emulsifying agents. But the mentioned products either are sparingly soluble or even insoluble in water; or they have, as for instance the pyridine, such a disagreeable odor that their use is unavoidably objectionable to the consumer. Furthermore these bases possess such a weak alkalinity that they are not capable of forming salts with weak acids, such as, for example, fatty or resinous acids. And their salts formed by reaction with strong or mineral-acids fail to have the above mentioned properties.

Now it has been found that these defects of pyridine and the other similar nitrogen-containing organic bases may be avoided by subjecting such bases to a hydrogenation process to produce piperidine or its homologues or the hydrogenated chinoline-bases, which products when combined with carboxylic or sulphonic acids are suitable as washing, emulsifying and wetting-out agents, the beneficial properties being due in part to the hydrogenated products themselves if the same are soluble in water, and in part due to properties of the reaction products gained through the reaction and/or retained from the initial materials.

Piperidine itself, for example, possesses a wetting power in rather weak water solutions, which makes it far superior to pyridine. Therefore by using it in the different technical processes, for instance in the textile-, leather- and paper industries, enormous advantages are obtained. For instance its reaction products or salts formed with oleic acid or ricinoleic acid, or with Turkey-red-oil, resinous acids and similar products possess a washing, cleansing and emulsifying power, which is far superior not only to that of ordinary soaps but also for instance to such soaps which besides the real soap-body contain higher molecular alcohols and similar emulsifying agents.

Another advantage is that the mentioned compounds are soluble without difficulty in organic solvents, in which property they differ from ordinary soaps, which are difficult to combine, particularly with hydrocarbons. Therefore they are fit especially for the production of water-soluble oils, as boring oils and textile oils, that is, for all those purposes in which the creation of dispersed systems is desired.

Example.—100 kgs. of piperidine are mixed with 290 kgs. of ricinoleic acid and simultaneously with the increase in temperature of the mass due to the exothermic nature of the reaction, a

yellow colored easily water soluble chemical combination is formed. This substance is capable of transforming hydrocarbons etc., into a condition in which they are emulsified with water. There are formed by the above mentioned example of this process, products which may be used as washing, cleansing, and wetting-out agents in different technical operations.

Instead of the piperidine as mentioned in the above example, its homologues and substitution products, and also hydrated chinoline-bases may be used; instead of the ricinoleic acid there may be used also other carboxylic acids of the aliphatic, aromatic or hydrocyclic series, or sulfonic acids, as for instance Turkey-red-oil, benzene- or naphthalene-sulfonic acids, etc.

I claim:

1. An emulsifying and wetting-out agent comprising, in combination, piperidine and ricinoleic acid combined by admixing the same in the proportions of 10 to 29 respectively.
2. An emulsifying and wetting-out agent comprising, in chemical combination, piperidine and Turkey-red-oil.
3. The process of producing an emulsifying and wetting-out agent which consists in mixing 10 parts of piperidine with 29 parts of ricinoleic acid, thereby forming a reaction product having such properties.
4. An agent for washing, emulsifying or wetting-out, containing a reaction product of an acid selected from the group consisting of sulphonic acids and carboxylic acids, with a hydrogenated heterocyclic base.
5. An agent for washing, emulsifying or wetting-out, comprising a reaction product of a sulphonic acid with a hydrogenated heterocyclic base.
6. An agent for washing, emulsifying or wetting-out, comprising a reaction product of a carboxylic acid with a hydrogenated heterocyclic base.
7. An agent for washing, emulsifying or wetting-out, comprising a reaction product of a carboxylic acid and piperidine.
8. An agent for washing, emulsifying or wetting-out, comprising a reaction product of a ricinoleic acid and piperidine.
9. An agent for washing, emulsifying or wetting-out comprising a hydrogenated heterocyclic base together with a salt of such a compound formed with an acid selected from the group consisting of sulfonic acids and carboxylic acids.

WALTHER SCHRAUTH. 110
